UNITED STATES PATENT OFFICE.

JOHN C. WILSON, OF BOSTON, MASSACHUSETTS.

PRINTING-TELEGRAPH SYSTEM.

SPECIFICATION forming part of Letters Patent No. 352,435, dated November 9, 1886.

Application filed January 4, 1886. Serial No. 187,518. (No model.)

To all whom it may concern:

Be it known that I, JOHN C. WILSON, of Boston, county of Suffolk, and State of Massachusetts, have invented an Improvement in Systems of Transmitting Stock-Quotations from a Central Office, of which the following description, in connection with the accompanying drawings, is a specification, like letters on the drawings representing like parts.

10 This invention has for its object to provide suitable instruments and arrangement of circuits, whereby stock-quotations may be transmitted from a main office over a main line, and at intervals or sub-stations along the main line be automatically repeated, that they may be received upon one or more stock-tickers placed in the vicinity of each sub-station.

15 In carrying out this invention I employ at the main station a single transmitter comprising co-operating devices to transmit impulses of opposite polarity immediately followed by an impulse of varying intensity over a main line, and at intervals or "sub-stations," as they may be termed, along the main line, I have inter-

20 posed suitable relays, respectively responsive to such impulses. The magnets respectively controlling the movements of the type-wheel and the operation of the printing mechanism of the several stock-tickers located in the vicinity of any one of the sub-stations are connected in local circuits respectively controlled by the armatures of the relays at the sub-stations, so that as the relays at the sub-stations respond to the transmitter at the main office they in 25 turn cause the magnets of the stock-tickers to similarly respond, thereby automatically repeating the quotation, that it may be received by the stock-tickers directly from the main office without the assistance of any retransmission at any point, as now frequently practiced.

30 Figure 1 shows a diagram of a system for sending stock-quotations directly from a main or transmitting station to the local stock-tickers; Fig. 2, a cross-section of the transmitting device shown in Fig. 1, and taken on the dotted line xx , and Fig. 3 a plan view of a stock-ticker which may be used in connection with this system.

35 40 The transmitter A, located at the main or transmitting station—as, for instance, at New

York, N. Y.—containing the main roll a , having stops or projections a' about its periphery, the levers a'' , motor a^2 to rotate the main roll a , the commutator a^3 , rotating in unison with said main roll, and the pens a^4 a^5 , connected, respectively, with the positive and negative poles of two main batteries, M M' , the opposite poles thereof being grounded, are all as usual, and operating, when the main roll and commutator is rotating, to send impulses of opposite polarity over the main line. The pen or contact-piece b , bearing upon the shaft upon which the commutator is mounted, connects the transmitting device with the main line 2.

45 The main roll a , set in operation by the motor a^2 , is stopped at any point desired by depressing one of the levers a'' , which raises the contact-piece 3, having a stud, 4, thereon, which latter, coming into the path of movement of one of the studs or projections a' upon the main roll, arrests its movement, thereby also arresting the movement of the commutator. While the main roll is rotating impulses of opposite polarity pass over the main line by means of the commutator.

50 The main batteries M M' are short-circuited to cut off a large percentage of the strength of the current by the wire 6 of a derived circuit connecting the pen or contact-piece c , bearing upon the main roll a , and the wire 5 of the said circuit connecting by means of a contact-screw, c' , a conducting-strip passing lengthwise of the transmitter, and to which the contact-pieces 3 are attached, so that when one of the levers a'' is depressed, and one of the studs 4 is made to come in contact with one of the projections a' of the main roll to arrest it, the circuit is completed. The currents of opposite polarity pass over the main line 2 and vibrate the armature e of a polarized relay, B, there preferably being several such relays located at intervals along the main line.

55 60 65 70 75 80 85 90 95 The armature e of the polarized relay is grounded and vibrates between two contact-points, 7 8, from one of which leads a local printing-circuit containing a local battery, B' , and one or more magnets, as m , controlling the operation of the type-wheels of one or more stock-tickers, the said local printing-cir-

cuit terminating in a ground. A neutral relay, C, is also connected with the main line 2, the normally-grounded armature of which is attracted as the current passes over the line, 5 and is released upon a reduction in the strength of the current striking the contact-point 10, from which leads a local circuit containing a local battery, B², and one or more magnets, as m', controlling the operation of the printing 10 mechanism of one or more stock-tickers.

The magnet m (see Fig. 3) controls the rock-shaft m³, which, by the intervention of the escapement m⁴ and ratchet-wheel m⁵, rotates the type-wheel m⁶, while the magnet m', attracting 15 its armature m⁷, forces the paper-printing mechanism against the under side of the type-wheel to thereby print a quotation indicative of the position of the type-wheel, all as usual. The impulses to which the polarized relay re- 20 sponds being reversals, the neutral relay is not affected; but when the current is weakened by short-circuiting the battery the neutral relay responds.

It is obvious that a suitable artificial resistance 25 might be momentarily interposed to effect the neutral relay, so I do not desire to limit myself to short-circuiting the main battery, as described. Thus it will be seen from the previous description that currents of opposite polarity passing over the main line control 30 the local printing-circuit and operate the type-wheel or wheels, while a reduction in the strength of the current controls the local circuit and operates the paper-printing mechanisms.

As shown in another portion of the diagram, Fig. 1, several stock-tickers (indicated by the letter S) are arranged in the same local type-wheel and paper-printing circuits, which 40 latter are branched, as occasion may require, so that at a certain city or town along the main line, if it is desired to locate several tickers, necessitating a current having many branches, a single polarized and neutral relay located at a convenient point may control them all. Near the end of the main line a suitable resistance-coil is located immediately beyond which the main line is grounded, while at the central office a Wheatstone bridge, w, and a rheostat, w', are interposed, the arms of the bridge being adjusted as usual in duplex telegraphy. A relay, R, controlling a signaling device, is contained 45 within the bridge, w, which is insensible to currents passing over the main line from the main station, but sensible to any change in the circuit—as, for instance, an accidental ground-break or cross-wire, which cuts out the resistance near the end of the line, thus 50 disturbing the balanced condition of the circuit. It will be seen that this feature is essential, owing to the fact that, suppose the line should be accidentally grounded midway, and a portion only of the polarized and neutral 55 relays located at the sub-stations should operate, stock-quotations would be received at

some points and not others, and serious results might occur between the brokers and individuals using them.

By the system herein described a central 70 office containing a transmitter constructed substantially as described may be located at, say, New York, N. Y., and a main line extend therefrom to a distant point—as, for instance, Boston, Massachusetts—and at intervals all along the line a pair of relays controlling local circuits, as described, may be interposed, and one or more tickers may be connected with the said local circuits and controlled as to their operation by the relays—as, 80 for instance, at any one or all of the large cities and towns between New York and Boston—thereby obviating the necessity of maintaining at each place where it is desired to locate one or more tickers a retransmitting- 85 station and an operator, which incurs so great expense as to preclude many persons from using the stock-tickers, and by retransmission of the quotation at every repeating-station, as now practiced, errors are liable to occur owing 90 to the carelessness of an operator.

I have herein shown a permanent resistance located at the remote station, and a relay connected with the circuit at the transmitting-station, and means for adjusting said relay 95 that it may be insensible to currents passing through it from the transmitting-station, but sensible to any change in the condition of the circuit between said relay and the remote station containing the resistance, to thereby inform the transmitting-station of any irregularity in the line; but such devices and arrangement of the circuits I do not herein claim, as the same form the subject-matter of another application filed by me October 6, 1886, 105 Serial No. 215,466.

I claim—

1. In a system for the distribution of stock-quotations, a main electric circuit containing a main or transmitting station and one or 110 more sub-stations, a single transmitter comprising co-operating devices located at the said main station that transmits impulses of opposite polarity over the said main line, and also impulses of different intensity, two relays located at each sub-station, one of which is responsive to the impulses of opposite polarity and the other responsive to the impulses of different intensity, two local circuits respectively controlled by the armatures of the 115 said two relays, magnets in said local circuits, and the type-wheel and paper-printing mechanism of one or more stock-receiving instruments operated by said magnets, substantially as described.

2. A transmitter for sending stock-quotations from a central office, consisting of a main rotating roll provided with studs or projections, printing-levers co-operating therewith, a commutator rotating in unison with the main 120 roll, two pins or contact-pieces connected respectively with the positive and negative poles 125

of the two main batteries co-operating with the commutator to send impulses of opposite polarity over the main line, a contact-piece co-operating with the main roll, and a conducting-strip to which the printing-levers are connected, said conducting-strip and contact-piece being connected by a circuit dividing the battery to thus vary the intensity of the current, all substantially as described.

10 3. The method herein described of distributing stock-quotations, which consists in transmitting impulses of two different characters

from a single main or transmitting station to several sub-stations, and in automatically repeating both kinds of impulses to one or more stock-tickers located in the vicinity of the said sub-stations.

In testimony whereof I have signed my name to this specification in the presence of two subscribing witnesses.

JOHN C. WILSON.
